HARVEY J. LOUNSBURY, OF GLEN ELLYN, ILLINOIS, ASSIGNOR TO W. H. MINER, INC.,
OF CHICAGO, ILLINOIS, A CORPORATION OF DELAWARE

RAILWAY DRAFT RIGGING

Application filed February 18, 1928. Serial No. 252,878.

This invention relates to improvements in railway draft riggings.

It is well known to those skilled in the art, that it is highly desirable, under the present 5 severe conditions of railroad operation, to provide draft gears having a much longer stroke than is now customarily employed, particularly in buff in order to absorb the exceedingly heavy buffing shocks. It is also 10 desirable to avoid any increase in train slack over that permitted by present day practice, which is ordinarily confined to $2\frac{3}{4}$ " for each draft gear. In providing such increased 15 shock absorbing capacity with longer buff action, it is necessary, from a practical standpoint, to confine the draft gear to the standard sill spacing of $12\frac{7}{8}$ " and to avoid any increase in the over-all height of the gear proper, in order that its center line may be 20 disposed in alignment with the center line of the coupler at the standard distance above the rails.

One object of my invention is to provide a very simple and efficient arrangement of 25 draft rigging for railway cars wherein is provided the desirable long travel or compression stroke in a buff action and which, at the same time, is restricted, in the draft action, to a relatively shorter travel or compression stroke, whereby to absorb efficiently and smoothly the heavy buffing shocks and cushion the draft shocks without increase of train slack.

Another object of my invention is to provide 35 a draft rigging of the character above indicated wherein is employed a friction shock absorbing device so associated with front follower acting means that the shock absorbing device is actuated or compressed 40 during a buffing stroke independent of any action of the front follower acting means during the initial portion of the compression stroke, whereby to obtain the desired long travel, the parts being further so arranged 45 that said follower acting means come into play during the entire draft action and are utilized to limit the draft stroke to one less than the buffing stroke.

Another object of my invention is to provide 50 a draft rigging arrangement of the

character indicated in the preceding paragraphs wherein undesirable overhang or undue projection of the friction elements of the friction shock absorbing device is avoided, while providing the desired longer 55 compression stroke, to the end that the efficiency and life of the friction device will not be impaired.

Another object of my invention is to provide a draft rigging of the character indicated wherein the ultimate buffing and draft forces are transmitted in the most efficient manner to the shell or cage of the friction shock absorbing device with uniform distribution of the load therearound, to thus 60 obtain the best column effect of the friction shell and minimize the tendency to bend the follower.

Other objects of the invention will more clearly appear from the description and 70 claims hereinafter following.

In the drawings forming a part of this specification, Fig. 1 is a longitudinal, vertical, sectional view of a portion of a railway car showing my improvements in connection 75 therewith, the parts being in full release. Fig. 2 is a horizontal, longitudinal, sectional view corresponding substantially to the line 2-2 of Fig. 1. Fig. 3 is a detail, transverse, vertical, sectional view corresponding to the 80 line 3-3 of Fig. 1. And Fig. 4 is a view similar to Fig. 2 illustrating a somewhat different embodiment of the invention.

Referring first to the embodiment of the invention illustrated in Figs. 1, 2 and 3, 85 10-10 denote the usual channel draft sills of a railway car underframe which, in the instance shown, constitute parts of the center sills and to which is connected the usual bolster indicated at 11, the same having a 90 combined center filler and abutment casting 12, the latter being forwardly extended and having transversely extending upper and lower vertical webs 13-13 which constitute the rear stop members of the draft gear. Said webs 13 are suitably reinforced by flanges 113 and it will also be noted that the two stop webs 13 are so separated, vertically, as to provide a combined guide and support for the rear end of the horizontal 95 100

yoke indicated generally by the reference character A. At the end of the car, the sills 10 are cut away to provide slots for the coupler key 14, the openings in the sills 5 being reinforced by castings 15—15 having elongated key slots 16—16 therein. In this embodiment of the invention, the front stops are provided by an upper casting B and a lower casting C each riveted to both sills. 10 Said upper casting B has a front vertical end wall 17 adapted to act as a striking plate, a horizontal web 18, a second horizontal web 19 downwardly offset from the web 18, and a vertical web 20 constituting the upper stop 15 proper, said web 20 being reinforced by a horizontal flange 21. The lower casting C comprises a horizontal bottom wall or web 22 and a vertically extending web 23 constituting the lower front stop proper, said web 20 20 23 being suitably reinforced by strengthening flanges 24.

In carrying out my invention, in addition to the yoke A, I employ a standard coupler D; a front follower E; and a friction shock absorbing device indicated generally by the reference character F. The follower E and device F are suitably supported in operative position by detachable saddle plates 25—25.

The yoke A is of the horizontal type, as 30 before mentioned, the side arms 26—26 thereof being integrally united at their front ends by a box-like section having side walls 27—27, a bottom wall 28 and top wall 29. The side walls 27 are suitably thickened, as best indicated in Fig. 2, to provide the necessary bearing for the coupler key 14 and the inner surfaces of said walls are outwardly flared as indicated at 127, to permit lateral motion of the coupler D. The top and bottom walls 29 35 and 28 are disposed at the outer end of the yoke and extend to points substantially in line with the usual horn of the coupler, the top wall 29 having a vertically extending flange 30 and the bottom wall 28 a depending flange 31. The upper flange 30 normally bears against the horn of the coupler and is adapted to engage the buffer plate 17 upon extreme buff movement. The side walls 27 40 are extended downwardly on each side of the yoke by means of vertical flanges 32—32, the lower edges of the latter riding upon and being supported by the lower wall 22 of the stop casting C. In this manner, the horizontal yoke is supported in proper horizontal 45 position at its front end and the necessary alinement of the coupler shank with the axis of the shock absorbing device maintained. It will further be observed that, in any operative position of the parts, there is no possibility of the coupler drooping or being 50 tilted upwardly, inasmuch as the yoke A and coupler are at all times maintained in their alined position.

The friction shock absorbing device F, as 55 shown, comprises a rectangular combined

friction shell and spring cage casting 33 within which is contained the usual main spring resistance (not shown). As shown, the friction shell proper is provided with liners 34 with which cooperate opposed friction shoes 35—35 and with the latter co-acts a pressure-transmitting wedge 36. In this connection, as clearly apparent from Fig. 1, it will be observed that the outer end face of the wedge 36 in full release condition of the gear, is located at a point beyond the open end of the shell an amount not greater than that now commonly employed in friction shock absorbing devices having only about $2\frac{3}{4}$ " travel. Also, it will be noted, that the co-acting wedge faces of the wedge 36 and the shoes 35—35 are disposed within the outer end of the friction shell. This is of importance in a friction shock absorbing device, inasmuch as undue overhang or extension of the shoes and wedge beyond the open end of the shell is avoided and consequently the tendency to spread laterally or create a "bell mouth" condition of the friction shell is eliminated or minimized. This arrangement of the shoes and wedge is obtainable in my construction by reason of the special formation of the front follower E and pressure-transmitting member about to be described.

Referring to the front follower E, the same is of heavy, thick formation and is provided on the front side thereof with a rectangular depression or recess 37 having a somewhat flaring mouth 38, the depth of the recess 37 being sufficient to accommodate the correspondingly shaped flange 39 of the pressure transmitting member 40 so that, upon sufficient movement of the coupler, the said flange 39 will lie completely within the recess of the follower E. On its rear face, the follower E is provided with a rectangular enlargement or boss 41 having beveled edges 42, said boss 41 being centrally located and of such area that it overlies the outer face of the wedge 36, but is small enough so as to permit its entrance within the open end of the friction shell 33 and thus permit the flat portions 43 on the inner face of the follower E to come into full face engagement with the outer end edges of the shell 33 at the end of a full compression stroke. The follower E is further provided with a rectangular centrally disposed opening 44 for the reception of the pressure-transmitting member 40. The pressure transmitting member 40 has the annular flange 39 previously described and inwardly of the latter is of rectangular formation to a point flush with the inner face of the boss 41. A shoulder is there provided by reducing the section of the pressure transmitting member to that of a square extension 45 which passes through an opening in the outer wall of the wedge 36 and engages the inner wall 46 of the wedge, as best shown in Fig. 1. At its front end, the pressure transmitting member or plunger 40

is provided with a forwardly extended tapered stud 47 which enters an opening 48 in the butt end of the coupler and by which the plunger is maintained centered with respect to the coupler.

- In a buff action, the friction shell 33 is held stationary by the rear stops 13-13. As the coupler moves inwardly, the pressure transmitting member or plunger 40 moves simultaneously therewith and directly actuates the wedge 36 of the friction gear, thus obtaining a compression stroke of the gear corresponding to the inward movement of the coupler. It will be observed that this movement occurs independent of any movement of the follower E until such time as the flange 39 of the plunger is fully seated within the recess 37 and thereafter the follower E will move in unison with the coupler and plunger until the balance of the compression stroke in buff is taken up, the limit being obtained when the outer portions of the follower E engage the end of the friction shell, as previously described. It will thus be seen that the ultimate buffing blow is well distributed through the follower to the end portions of the shell and through the latter as a column to the rear stops 13-13. In actual practice, the compression buff stroke will preferably approximate 5" or 6". In draft, outward movement of the coupler D causes a simultaneous movement of the yoke A and the latter in turn moves the shell 33 forwardly. During this draft action, the wedge 36 of the friction device bears against the then stationary front follower E and consequently the friction device is actuated, as will be understood. The draft action continues until the shell 33 comes into engagement with the follower E and this stroke will preferably be limited to about 2 3/4", the present standard practice. During the draft action, it will be observed that the plunger 40 is inactive and may or may not move slightly, dependent upon the amount of friction between it and the coupler. It will also be observed that the ultimate blow in the draft action is transmitted most efficiently through the shell acting as a column to the outer portions of the follower E and from the latter to the upper and lower front stops B and C.
- Referring to the modification shown in Fig. 4, the arrangement of coupler, front follower, friction shock absorbing device and pressure transmitting member or plunger is the same as that shown in the first three figures. In the Fig. 4 modification, the arrangement is shown adapted to the use of a yoke of the vertical type, the same being indicated at G. This yoke, per se, is or may be the same as that disclosed in my application, Serial No. 238,751, filed on or about December 9, 1927, now Patent 1,743,042, granted January 7, 1930, and need not be here described in detail. In this modifica-

tion of the invention, vertical front stop lugs 123 and 123 are provided with which the front follower engages, said front stops being formed integral with end castings having the coupler key slots 116 formed therein.

The rear stops are arranged vertically as indicated at 113'-113', the same being preferably cast integrally with the bolster center filler casting 112. The operation of the device shown in Fig. 4 is obviously the same as that shown in Figs. 1, 2 and 3 and above described.

I have herein shown and described what I now consider the preferred manner of carrying out my invention, but the same is merely illustrative and I contemplate all changes and modifications that come within the scope of the claims appended hereto.

I claim:

1. In a railway draft rigging, the combination with a shock absorbing mechanism including a friction shell open at one end, and friction means within the shell, said shell and friction means being relatively movable lengthwise of the mechanism and said shell being held against movement inwardly of the rigging, said shell being movable outwardly in draft; of a main follower, said follower and shell being relatively movable toward and away from each other, and said follower being held against outward movement, said follower having a main portion engageable with said shell to limit relative movement of the shell and follower, and an inwardly offset central portion adapted to enter the shell, said offset portion being engageable with said friction means during a draft action; and a pressure transmitting plunger adapted to receive buffing forces extending through said follower and relatively movable with respect to the same, said plunger engaging the friction means to actuate the friction means during inward or buffing movement of the plunger.
2. In a railway draft rigging, the combination with a shock absorbing mechanism including a friction shell open at one end and friction means within the shell, said shell and means being relatively movable lengthwise of the mechanism, and said shell being held against movement inwardly of the rigging in buff, said shell being movable outwardly in draft; of a coupler; a main follower relatively movable with respect to the friction shell lengthwise of the rigging and being held against outward movement in draft, said follower having a main portion engageable with the shell to limit relative movement of the shell and follower, and a central projection on one side of said follower adapted to enter the shell and engage said friction means to actuate the same when the shell and follower are moved relatively to each other during movement of the coupler in one direction; and a pressure transmitting

plunger extending through the follower and movable with respect thereto lengthwise of the mechanism, said plunger when moved inwardly in buff engaging the friction means to 5 actuate the same.

3. In a railway draft rigging, the combination with a coupler; of shock absorbing means including a friction shell and friction means cooperating therewith, said shell being movable outwardly in draft and held 10 against movement inwardly of the rigging in buff; a main follower held against outward movement in draft, said main follower and shell being movable relatively to each 15 other lengthwise of the mechanism, the follower having a portion engageable with the shell to limit relative movement of the shell and follower, said follower also having an opening therethrough and a boss surrounding 20 said opening on the side of said follower facing the friction shell and adapted to enter the shell and engage and actuate said friction means; and a pressure transmitting plunger interposed between the coupler butt and the 25 friction means, said plunger being freely reciprocal in the opening of said follower, said follower having a depression in the face thereof on the side opposite to said boss adapted to accommodate the butt end 30 portion of the coupler shank upon full inward movement of the coupler in buff.

4. In a railway draft rigging, the combination with a front follower held against outward movement in draft; of a friction shock 35

absorbing mechanism including a friction shell open at the forward end and friction means within the shell, said shell being held against inward movement in buff, said shell and follower being relatively movable lengthwise of the rigging, and relative movement of said shell and follower being limited by engagement of the outer end of the shell with said follower; a coupler having greater movement in buff than in draft, the butt end of 70 said coupler being movable inwardly beyond the outer end face of said follower when the follower is at its outer limit of movement, said follower having a projection on the inner side thereof adapted to freely telescope 75 within the open end of the shell and engage said friction means, said follower being recessed on the outer side to accommodate the inner end of the coupler butt when the latter is moved inwardly in buff, said follower 80 having an opening therethrough; and a pressure transmitting plunger extending through the opening of the follower and freely movable therein, said plunger being interposed between the butt end of the coupler and the 85 friction means and transmitting the actuating force from the former to the latter during a buffing action and affording a longer stroke 90 of the coupler in buff than in draft.

In witness that I claim the foregoing I 95 have hereunto subscribed my name this 8th day of Febr. 1928.

HARVEY J. LOUNSBURY.
